UNITED STATES PATENT OFFICE.

FRANK W. KELLOGG, OF REEDSPORT, OREGON.

HAIRBRUSH.

Application filed May 1, 1926. Serial No. 106,095.

This invention relates to brushes, and more particularly to hair brushes, and has for its object, to improve the sanitary condition of the brush, and to provide a brush frame adapted to maintain and hold within the frame structure, brush carrying removable units, which are interchangeable, one with the other, in any position within the brush, and the terminal ends of the brush carrying frame being uniform in shape.

Applicant now has a pending application in the United States Patent Office, filed March 5, 1925, Serial Number 13,170, the object of which is similar to the application filed herewith.

Further objects of my invention, consists in new, novel, and useful means for maintaining the individual unit brush members, in relation with each other, and in fixed position within the frame.

A further object of my invention, consists of the making of the same of few parts, and that are adapted for general use in brushes, as well as in hair brushes, and one that may be assembled and disassembled by those inexperienced in mechanical things.

With these and incidental objects in view, the invention consists in certain novel features of construction and combination of parts, the essential elements of which are set forth in the appended claims, and a preferred form of embodiment of which is hereinafter shown with reference to the drawings which accompany and form a part of this specification.

In the drawings:-

Fig. 1 is a perspective view of the assembled brush.

Fig. 2 is a cross sectional view, taken on line 2—2 of Fig. 1, looking in the direction indicated.

Fig. 3 is a side elevation, in section, here illustrated as being disassembled.

Fig. 4 is a sectional end view, taken on line 4—4 of Fig. 1, looking in the direction indicated.

Fig. 5 is a perspective view of the back closure.

Fig. 6 is a fragmentary perspective view of the mid-section of the brush, made to feature the spring member for maintaining the brush units under compression.

Fig. 7 is a perspective view of one of the brush units.

Fig. 8 is a cross section, taken on line 8—8 of Fig. 2, looking in the direction indicated.

Like reference characters refer to like parts throughout the several views.

The supporting element of my device is the inner back 2, which is provided with a handle 1. This inner back is made of thin light weight material, and to further materially reduce its weight I have provided oppositely positioned arcuate indentations as shown in Fig. 6. At the point where the inner back joins the handle 1, and spaced therefrom, I have formed an inwardly projecting portion 3, the purpose of which will be explained later.

Embracing the inner back 2, I provide an outer back 6. This outer back is provided with vertical side walls 12 and 13 and an inwardly turned end wall 5, and when the outer back is in position upon the inner back, as shown in Fig. 1, and in the more detailed cross section view of Fig. 2, the inwardly turned end wall 5, and the inwardly projecting portion will each be spaced at approximately the same distance from the inner back 2. In order to secure the outer back to the inner back, I have provided outstanding pins or projections 16, at the junction of the inner back 3 and the handle 1, and through the inner ends of the walls 12 and 13 have been formed the holes or eyes 15, which are to fit about and embrace the pins 16. The side walls are bent slightly outward when the eyes 15 engage or disengage the pins 16. This is particularly illustrated in Fig. 4.

In my brush I prefer to use interchangeable bristle carrying members 7, shown in Fig. 7. The member 7 I prefer to have constructed of light metal, or of some other non-absorbent material, and I also prefer to have but one row of bristles on each bristle carrying member. The bristles 9 may be assembled to the member by any well known method, though I use the groove method, wherein a groove 8 is formed in line with the bristle carrying holes, and a non-corrosive wire is passed along the groove, and sews or ties each tuft of bristles in its respective hole. After the bristles are in place, the groove 8 should be filled with a non-absorbent and non-corrosive material to prevent the entry of foreign matter therein. In future references to the individual bristle carrying members in this specification, I shall refer to the same as brush elements.

Referring again to Fig. 3, a brush element 7 is shown positioned within the inner and

outer back assembly, and the inwardly projecting portion 3 and the inwardly turned end wall 5, slightly overlap the outer ends of the brush elements. As the brush elements are slightly less in vertical cross section than the width between the inwardly projecting portion 3 and inwardly turned end wall 5, respectively, and the inner back 2, the brush elements will be held loosely upon the inner back, within the assembly, by means of the elements 3 and 5 aforesaid. It is desirable that there be no play or movement of the brush elements, and to avoid this I have provided an arcuate leaf spring 4, which is placed between the inner back 2 and the brush elements 7. This will cause the brush elements to bear upon, at their outer ends, the inwardly projecting portion 3 and the inwardly turned end wall 5, and thus movement of the brush elements will be eliminated.

While in Figs. 1 and 3, I have shown the brush backs carrying five rows of brush elements, this number is merely for the purpose of illustration, and inasmuch as the width of the backs, or of the bristle elements may be altered, it will be seen that the number of brush elements is optional.

While the form of mechanism herein shown and described is admirably adapted to fulfill the objects primarily stated, it is to be understood that it is not intended to confine the invention to the one form of embodiment herein shown and described, as it is susceptible of embodiment in various forms, all coming within the scope of the claims which follow.

What I claim is:—

1. A hair brush embodying an inner back, including a handle; an outer back embracing the inner back; an inwardly turned end wall formed upon the outer back; an inwardly

projecting portion formed on the inner back; one or more brush elements disposed upon said inner back and having the ends thereof positioned below the inwardly turned end wall and the inwardly projecting portion aforesaid; and a yielding element disposed between said brush elements and said inner back, and causing the ends of said brush elements to engage, the inwardly turned end wall and the inwardly projecting portion aforesaid.

2. A hair brush embodying an inner back, including a handle; an outer back embracing the inner back; said outer back member being provided with vertical side walls and an inwardly turned end wall; oppositely positioned outstanding pins formed on the inner back; an eye formed in the inner end of each of said walls; said eyes adapted to embrace said pins; an inwardly projecting portion formed on the inner back; a plurality of brush elements disposed upon said inner back and having the ends thereof positioned below the inwardly turned end wall and the inwardly projecting portion aforesaid; and a yieldable element disposed between said brush elements and said inner back, and causing the ends of said brush elements to engage the inwardly turned end wall and the inwardly projecting portion aforesaid.

3. A hair brush embodying a pair of embracing back members; a handle provided for one of said back members; means for maintaining said back members in engagement with each other; oppositely positioned and inwardly disposed projecting portions formed on said back members; brush elements positioned between said projecting portions and said back members; and a spring element positioned between said brush elements and said back members.

FRANK W. KELLOGG.
